UNITED STATES PATENT OFFICE.

EDWARD A. HALBLEIB, OF ROCHESTER, NEW YORK, ASSIGNOR TO NORTH EAST ELECTRIC COMPANY, OF ROCHESTER, NEW YORK, A CORPORATION OF NEW YORK.

POWER-TRANSMISSION MECHANISM.

1,165,966.

Specification of Letters Patent. Patented Dec. 28, 1915.

Application filed May 5, 1913. Serial No. 765,714.

To all whom it may concern:

Be it known that I, EDWARD A. HALBLEIB, a citizen of the United States, and resident of Rochester, in the county of Monroe and 5 State of New York, have invented certain new and useful Improvements in Power-Transmission Mechanism, of which the following is a specification.

This invention relates to mechanism or 10 gearing which is adapted to transmit power from one to the other of two devices, such as an engine and an electric generator, so that either of said devices may actuate the other, but at speed-ratios differing according 15 as one or the other device constitutes the source of power. Mechanism of this type is frequently employed in connection with a system in which an internal-combustion engine and an electric generator are employed, 20 the engine, during its normal operation, driving the generator to produce electricity and charge a storage-battery, while the generator may be employed, when necessary, as an electric motor to start the operation of 25 the engine.

In my pending application for Letters Patent of the United States filed February 4, 1913, Serial No. 747,185, I have disclosed mechanism of the type in question, this 30 mechanism including a shiftable clutch-member which is moved to one position or another, according as the gearing is to be employed to transmit power from one to the other of the devices coöperating therewith, 35 and the present invention relates particularly to improvements in the mechanism shown in said application. In that mechanism the shiftable clutch-member is provided with teeth adapted to coöperate with 40 teeth upon a rotary element which constitutes the means whereby the gearing may be connected with an engine, and the clutch-teeth in question are beveled in order that they may have an automatic disengaging 45 action when the shiftable clutch-member tends to overrun said rotary element, in order that it may be possible for the motor-generator at all times to freely overrun the engine. When the engine is running slowly, 50 however, its speed of rotation fluctuates with each pulsation of the engine, with the result that more or less back-lash and chattering may occur between the beveled clutch-teeth.

55 One object of the present invention is to

avoid this result, and to this end I introduce, in the present gearing, a roller-wedge clutch which is adapted to accommodate itself to such slight inequalities in the driving-motion without noise or jar, and which 60 permits the use of square or abrupt engaging-members or teeth, on the shiftable clutch-member, which may be fitted closely so as to avoid any substantial play or back-lashing when the clutch-members are in en- 65 gagement.

In the gearing of my said application the arrangement of the clutch-members, and of the speed-reducing gears through which the motor-generator actuates the engine, is such 70 that in case of a premature explosion or back-kick in the engine the gearing may operate to arrest the forward movement of the armature of the motor-generator, and throw it into rapid rotation in the reverse 75 direction. This action subjects the mechanism and the armature to a severe strain, and it has the further disadvantage of subjecting the clutch-mechanism to a severe strain in case the shifting clutch-member is 80 shifted while the armature is still rotating reversely.

Accordingly, another object of the invention is to protect the mechanism against the strains just described, and to this end I interpose, between the generator-shaft and the rotary element of the gearing to which it is connected, a friction-coupling or slip-device which connects the parts with sufficient force 85 to secure them against relative rotation during normal operation of the apparatus, but which will yield under the unusual conditions arising in consequence of a back-kick in the engine. In case of such a back-kick this friction-coupling operates, in the first place, 90 to yield when the movement of the gearing is first reversed, so that the rotation of the armature is not so suddenly arrested and reversed; and it has the further advantage 95 that after the rotation of the armature has been so reversed, and the shiftable clutch-member is thrown into coöperation with the engine-connected rotary element, the inertia of the armature in its reverse rotation is absorbed principally by the slip-connection, so as to relieve the clutch-mechanism from 100 severe strain.

In the accompanying drawings:—Figure 1 is a vertical, median, longitudinal section of a gearing embodying the present invention; 110

Fig. 2 is a vertical section on the line 2—2 in Fig. 1, looking from right to left in the latter figure; Fig. 3 is a left-hand elevation of the shiftable clutch-member; and Fig. 4 is a side-elevation of the combined friction-coupling and Oldham coupling.

The invention is illustrated as embodied in a power-transmission mechanism which is similar, in general, to the mechanism or gearing of my said application. It comprises two coaxial shafts or rotary elements, which are hereinafter designated, for convenience, as the "primary rotary element" and the "secondary rotary element." The primary rotary element, as shown in Fig. 1, is a shaft 5, which may be connected, in any convenient manner, with the engine with which the mechanism is to be employed. This shaft is journaled in a casing 7, by means of ball-bearings 8. The secondary rotary element is a shaft 6, also mounted in the casing coaxially with the shaft 5, the left-hand end of the shaft 6 having a reduced portion 17 which is journaled in a central recess in the shaft 5, while the shaft 6 is also supported, through an intermediate concentric element hereinafter described, by a ball-bearing 9 mounted in the casing. A third rotary element, coaxial with the elements 5 and 6, is in the form of a shaft 10, which may be, and is illustrated as, the armature-shaft of the motor-generator which coöperates with the power-transmission mechanism.

The speed-reducing gears, through which the motor-generator may actuate the primary rotary element and the engine, comprise a pinion 11, which is journaled loosely upon the shaft 6 and supported directly by the ball-bearing 9, this pinion, in turn, serving as a bearing for the direct support of the shaft 6, as shown in Fig. 1. The pinion 11 meshes with a gear 12, which is journaled loosely upon a countershaft 13 fixed in the casing 7. Integral with the gear 12 is a second pinion 14, which meshes with a gear 15 concentric with the shaft 5, this gear being supported upon and connected with the shaft 5 by means of a roller-wedge clutch, through which the gear may drive the shaft. The shaft 5 is provided with an enlarged portion or shell 19 at its inner end, this shell having recesses 26 with inclined surfaces with which rollers 27 coöperate. These rollers engage a smooth internal clutch-surface 28 on the gear 15, and they are controlled by spring-pressed plates 29, which tend to move them toward the shallowest parts of the recesses 26. The rollers are held in the recesses 26 by snap-rings 45, which are omitted from Fig. 2 for the sake of clearness. The arrangement of these parts, as shown in Fig. 2, is such that when the motor-generator rotates in its normal direction, and acts as an electric motor, the gears and the clutch-members are moved in the direction of the

arrows in Fig. 2, and the gear 15, acting through the roller-wedge clutch just described, rotates the shaft 5 and actuates the engine in a direction to start it. As soon as the normal operation of the engine commences, however, the roller-wedge clutch permits the engine and the shaft 5 to overrun the speed-reducing gearing freely.

To control the operative connection between the shaft 6 and the pinion 11 on the one hand, or the direct connection between the shaft 6 and the shaft 5 on the other hand, a shiftable clutch-member is employed, this member being slidably mounted upon a square portion 16 of the shaft 6. This clutch-member has a transverse recess 24 which may coöperate with corresponding teeth 25 upon the left-hand end of the pinion 11, one of these teeth being shown in dotted lines in Fig. 1. When the engine is to be started the clutch-member 18 is shifted to the right, so as to engage the teeth 25, and the pinion 11 may then be rotated, as above described, by the shaft 6. After the engine has been started, however, the clutch-member 18 is moved to the left, to disengage the teeth 25, and in its left-hand position it coöperates with clutch-members through which the shaft 5 may rotate the shaft 6 to drive the motor-generator. Upon the left-hand face of the clutch-member 18 are clutch-teeth 23, shown in Fig. 3. These teeth are adapted to engage a transverse recess 22 (see Fig. 2) formed in a clutch-member 20, which is located within the enlargement or shell 19 on the shaft 5. The clutch-member 20 constitutes an element of a roller-wedge clutch, being provided, as shown in Fig. 2, with a series of inclined recesses containing rollers 21. These rollers engage a smooth clutch-surface on the inside of the shell 19, and when the shaft 5 and the shell 19 are rotated in the normal direction by the engine the rollers act to grip the clutch-member 20 and cause it to rotate with the shaft 5. With the shiftable clutch-member 18 in the position shown in Fig. 1 this rotation of the clutch-member causes the clutch-member 18 and the shaft 6 to rotate in unison with the shaft 5, and the shaft 6, in turn, rotates the armature-shaft 10, through the slip-connection hereinafter described, thus actuating the motor-generator and causing it to generate electricity. During this action of the power-transmission mechanism, if the speed of the engine becomes very much reduced and its rotation irregular, the momentary retardations in the speed of the shaft 5 are absorbed by the automatic overrunning action of the clutch-member 20, which is permitted by the frictional engagement of the rollers 21 with the member 19; while at each succeeding acceleration of the shaft 5 these rollers take

hold, without noise or lost motion, to drive the clutch-member and the other parts. Owing to this arrangement the clutch-teeth 23, and the recess 22 with which they co-operate, may be made with abrupt or square engaging-surfaces, as shown in Fig. 1, so that no back-lash or lost motion occurs between them. The teeth 23 may, however, be slightly beveled at their ends, as shown, 10 to facilitate their engagement with the recess 22 when the clutch-member 18 is shifted as above described.

Any convenient means may be employed for shifting the clutch-member 18, but I 15 have illustrated means for this purpose similar to those disclosed in my said application. The clutch-member 18 is provided with an annular flange 30, which is embraced by the slotted end of an arm 31. 20 This arm is fixed to a rod 32, which is guided to slide horizontally in the casing 7 and is forced in one direction by means of a spring 33 coiled around the rod. The arm 31 and the rod are moved in the opposite direction by means of an arm 43, which 25 engages the hub of the arm 31 and swings about a vertical axis. The arm 43 is moved manually in any convenient manner. In my said application I illustrated an electric switch and mechanism for actuating 30 simultaneously this switch and the arm 43. A similar arrangement may be employed in the present case, and I have shown a casing 44 mounted on the top of the casing 7 and adapted to contain the switch. Upon the top of the casing 44 is an arm 35 adapted for manual operation, and the 35 connections between this arm and the arm 43 are illustrated diagrammatically by 40 broken lines 34.

The slip-connection between the shafts 6 and 10 is shown in Figs. 1 and 4. The shaft 6 has a squared portion 36 upon which is mounted a shell 37 with a conical inner 45 surface. A conical friction-member 38 co-operates with the member 37, and is pressed constantly against it by means of a spring 39 coiled about the shaft 36. The left-hand end of this spring engages a shoulder 50 on the member 38, while its right-hand end is seated against a collar 40 screwed upon the shaft 6. The slip-connection is shown as combined with an Oldham coupling to 55 compensate for slight variations in the axial positions of the shafts 6 and 10. To this end a coupling-member 42 is keyed upon the shaft 10, and an intermediate or floating coupling-member 41 is interposed between the members 38 and 42, these three parts 60 having the usual inter-engaging tongues and grooves characteristic of an Oldham coupling.

During the normal operation of the mechanism the friction between the parts 37 and 65 38 is sufficient to prevent any relative rota-

tion, and to cause the shaft 6 to drive the shaft 10 or vice versa. Upon any sudden and powerful reversal in the direction of movement of the shaft 6, however, the slip-connection yields, the part 38 rotating with 70 in the part 37, so that no severe strain can be imparted either to or from the generator-shaft 10.

My invention is not limited to the embodiment thereof hereinbefore described and 75 illustrated in the accompanying drawings, but it may be embodied in various other forms within the nature of the invention as it is defined in the following claims.

I claim:—

1. Power-transmission mechanism having, in combination, a primary rotary element; a secondary rotary element coaxial therewith; gear-connections between said elements whereby the secondary element may 85 actuate the primary element at a reduced speed; and means for connecting said elements to permit the primary element to actuate the secondary element without change of speed, said means comprising a 90 shiftable clutch having one member connected with one of the rotary elements; and an overrunning clutch connecting the other member of the shiftable clutch with the other rotary element. 95

2. Power-transmission mechanism having, in combination, an engine-connected rotary element; a generator-connected rotary element; means, for connecting said elements to permit the engine-connected element to 100 drive the generator-connected element, including an overrunning clutch to permit the generator-connected element to overrun the engine-connected element; and means co-operating with a portion of said first named 105 means, for connecting the rotary elements independently of said overrunning clutch, to permit the generator-connected element to drive the engine-connected element.

3. Power-transmission mechanism having, 110 in combination, an engine-connected rotary element; a generator-connected rotary element; means, including a manually-operable clutch, for connecting said elements to permit the engine-connected element to drive 115 the generator-connected element, said means including also an overrunning clutch to permit the generator-connected element to overrun the engine-connected element; and means, co-operating with said manually- 120 operable clutch, for connecting said elements to permit the generator-connected element to drive the engine-connected element, said means including also an overrunning clutch to 125 permit the engine-connected element to overrun the generator-connected element.

4. Power-transmission mechanism having, in combination, three rotary elements; gearing and an overrunning clutch through which the secondary rotary element may 130

actuate the primary rotary element at reduced speed, while the overrunning clutch permits the primary rotary element to overrun the gearing; a shiftable clutch operable 5 to connect the secondary rotary element alternatively with said gearing, for the purpose aforesaid, or with the primary rotary element, independently of the gearing, to permit the primary rotary element to actuate 10 the secondary rotary element; and slip-connections between the secondary rotary element and the third rotary element, said connections being yieldable to a force greater than that encountered in the normal operation of the mechanism.

5. Power-transmission mechanism having, in combination, an engine-connected rotary element; a generator-connected rotary element; and means for connecting said elements to permit either to drive the other, said means including an overrunning clutch, through which the engine-connected element drives the generator-connected element but which permits the latter to overrun the 20 former, and a manually operable clutch 25

through which the generator-connected element may drive the engine-connected element.

6. Power-transmission mechanism having, in combination, an engine-connected rotary 30 element; a generator-connected rotary element; and means for connecting said elements to permit either to drive the other, said means including an overrunning clutch through which the engine-connected element 35 drives the generator-connected element, but which permits the latter to overrun the former, a second overrunning clutch through which the engine-connected element may be driven by the generator-connected element 40 but which permits the former to overrun the latter, and manually operable clutch-members by which the connecting-means may be thrown into operation for the two described functions alternatively.

EDWARD A. HALBLEIB.
